Application August 25, 1944, Serial No. 551,203

8 Claims. (Cl. 178—5.6)

1

This invention relates to television systems and more particularly to a multiple television system and means f_1 for selectively receiving any desired one of the programs thereof.

In my Patent No. 2,437,300, issued on March 9, 1948, I disclose a television transmitting method and system for transmitting simultaneously a plurality of television programs from a single vantage point such as from the top of the highest building of a city or from a tower located at some high elevation within the area served. The picture programs are transmitted on separate carrier frequencies while the sound signals accompanying each program are transmitted as separate channels of a multi-channel carrier on still another frequency. Synchronizing signals common to all of the picture programs are transmitted as one of the channels of the multi-channel carrier.

It is an object of this invention to provide in combination with such transmitting method and system a television receiving method and means for selectively receiving any one of the multiple television programs transmitted.

Another object is to provide a television receiver for receiving picture signals on one carrier, and sound and/or synchronizing signals on another carrier.

Another object is to provide a method and means for obtaining certain synchronizing pulses from a multi-channel train of pulses wherein the shape and/or timing characteristics of the pulses of the train differ according to the use intended of them.

According to one of the features of the present invention the receiver is provided with directive antennas aligned with the antennas of the transmitting station. By this arrangement substantially equal reception is had for each of the different television programs. The picture signal carriers, being distinguished by different carrier frequencies, are selected by frequency tuning. The sound signals accompanying each picture program being transmitted over a multi-channel carrier are selectively segregated according to the channel corresponding to a selected television program. The picture signal and sound channel selection may be coordinated so that a corresponding sound channel is obtained automatically by the tuning-in of each picture program.

The synchronizing feature of the invention includes the provision of means for segregating the channel synchronizing signals from the multi-channel carrier for synchronizing the picture reproduction operation of the receiver regardless

2

of change in the tuning-in of different picture programs. This is made possible by employing at the transmitter the same synchronizing signals for each of the different picture programs. In addition to this use of the synchronizing signals, they may be used to synchronize and/or stabilize selective reception of the sound channels.

The above and other objects and features of the invention will become more apparent upon consideration of the following detailed description to be read in connection with the accompanying drawings, in which:

Fig. 1 is a block diagram of a television system incorporating the features of my invention;

Fig. 2 is a graphical illustration used in explaining the operation of the system shown in Fig. 1;

Fig. 3 is a schematic diagram of a pulse width discriminating circuit used in the system of Fig. 1; and

Fig. 4 is a schematic diagram of a pulse time demodulator that may be employed in the system of Fig. 1.

For simplicity of illustration I disclose a transmitter system adapted to transmit simultaneously three picture programs as indicated by the three accompanying sound channels 1, 2 and 3 in graph *b* of Fig. 2. The transmitter 4 shown in

Fig. 1 is provided with a tower 5 having antennas 6, 7, 8 and 9. These antennas may be of any known omnidirectional type. Antenna 6 is connected to the transmitter 4 for transmission of a multi-channel pulse train such as illustrated in graph *b* of Fig. 2, on a carrier frequency f_0 . Antennas 7, 8 and 9 are connected to the transmitter for simultaneous transmission of three separate picture programs each similar to the video signal of graph *a*, Fig. 2, over separate carrier frequencies f_1 , f_2 , and f_3 . The video signal of each picture program such as represented by graph *a* of Fig. 2 includes picture signals 10, horizontal blanking pulses or intervals HB and vertical blanking pulses or intervals VB. While the

picture signals 10 are indicated as line signals such as obtained by line scanning, such showing is given by way of example only, since it is recognized that other types of television scanning may be employed without departing from the principles of this invention. While the transmitter system is indicated for only three picture transmissions and one multi-channel transmission, it will be clear that additional picture programs as well as other types of broadcasts may be included.

The receiver 11 includes two receiving antennas

12 and 13, preferably of the directive character arranged for alignment with respect to the antennas 6 to 9 of the transmitting tower 5. Associated with the antenna 12 and 13 are the usual R.-F. and I.-F. amplifier converter units 14 and 15 tunable for reception of the appropriate carriers. The unit 14 may be tuned to either of the carriers f_1 , f_2 , or f_3 , for selective reception of any one of the picture programs. It will be understood, of course, that the amplifier units 14 and 15 may be made tunable for receiving other broadcasts as well, and the directive antennas 12 and 13 may also be made adjustable if desired. The output of the amplifier 14 is applied to a detector 16 for translation of the intermediate frequency signals into a video signal such as shown in graph a. The video signal is applied to a picture reproducer 17 whereby the picture is reproduced according to known methods.

The multi-channel carrier received by antenna 13 and amplifier 15 is detected at 18 to produce a train of channel pulses such as indicated by graph b. For three sound channels the train includes three different series of signal pulses 1, 2 and 3, and a fourth channel comprising horizontal and vertical synchronizing pulses H and V. The horizontal synchronizing pulses H are of a width greater than the signal pulses 1, 2 and 3 while the vertical synchronizing pulses V are of still greater width. If desired, pulse shape characteristics other than width may be used for distinguishing the horizontal and vertical synchronizing pulses from each other and from the pulses of the other channels.

The multi-channel signals are applied over connection 18a to pulse width discriminator 19 which may be of any suitable character capable of distinguishing between the signal pulses and the horizontal and vertical synchronizing pulses. A suitable width discriminating circuit for this purpose is illustrated in Fig. 3. The circuit includes limit clipping stage 20 as an input coupler which limits all input pulses to substantially the same amplitude, and also inverts the input pulses from a positive polarity to negative polarity. The output pulse energy from stage 20 is applied through a resistor R to a shock excitable L.-C. circuit 21. Connected across the tunable circuit 21 is a vacuum tube 22, the cathode 23 of which is connected to the input side of the circuit 21, while the anode 24 is connected to the opposite side 25 of the tunable circuit. The side 25 is also connected to a source of anode potential 26. The pulse energy from the anode connection 27 is applied to the control grid 28 of the tube 22 so as to block the conduction between the cathode 23 and the anode 24 while the pulse energy is applied to the circuit 21. The undulations produced in the circuit 21 in response to pulse energy over anode connection 27 are taken off through a connection 29 for application to a threshold clipping amplifier 30 and through a connection 31 to a second threshold clipping amplifier 32.

Graph c of Fig. 2 illustrates the pulse width discriminating function of the circuit 19. When the leading edge 33 of a horizontal synchronizing pulse H, for example, reaches the L.-C. circuit 21 it shock excites the circuit into an oscillatory condition as indicated by the undulation 34 of graph c. Where the circuit 21 is tuned to a resonant frequency one-half the period of which corresponds to the duration of the wider pulse V, graph b, it will be apparent that the trailing edge 35 of the pulse H occurs before the undulation 34 has gone through its normal duration. The edge

35 accordingly shock excites the circuit 21 in the opposite polarity direction thereby producing an oscillatory condition 36 out of step with undulation 34. This results in an average oscillatory condition as represented by the positive undulation 37.

When the vertical synchronizing pulse is applied to the circuit 21, the leading and trailing edges thereof are separated by an interval corresponding exactly to one-half the period of resonant frequency so that when the trailing edge 38 is applied to the circuit 21 the shock effect thereof occurs at the point where the initial undulation 34 is crossing the zero axis thus adding to the oscillatory effect produced by the leading edge. This results in a maximum undulation 39 greater than the undulation 37. As regards the effects of the pulses of the signal channels 1, 2 and 3 it will be readily apparent that these pulses being much narrower in width will only produce a small ripple effect as indicated at 40, graph c. This clearly is due to the fact that the leading and trailing edges operate substantially in opposition one to the other in their action upon circuit 21.

The oscillatory condition established in the circuit 21 would normally continue as a damped wave except for the action of tube 22. The pulse energy applied to the circuit 21 is negative in polarity, as hereinbefore stated, and by applying this negative energy to grid 28 the tube 22 is maintained opened for the duration of the pulse. Since the pulse energy is dissipated the blocking energy on grid 28 is removed permitting the tube to conduct as soon as the oscillatory energy again goes negative. This condition permits the tube to absorb the oscillatory energy of the oscillation when the positive undulation reaches the zero axis thereby preventing a carry over of oscillatory energy from one pulse to the next. For a further discussion of the width discriminating circuit reference may be had to the Patent to E. Labin and D. Grieg, No. 2,440,278, issued April 27, 1948.

In order to obtain horizontal synchronizing pulses corresponding to the leading edges of the pulses H and V the output energy of the circuit 19, graph c, is applied to the threshold clipper 30 biased to clip the negative undulations of the output energy at a level 41 which clears the ripple effect 40 produced by the signal channels. By applying the clipper output to a shaper 42 which may comprise a differentiator circuit only or additional pulse shaping circuit, output pulses 43, graph d, are obtained timed substantially to the leading edge of the pulses H and V. These pulses 43 are then applied over connection 44 to the picture reproducer 17 to control the horizontal sweep circuit of the reproducer.

To obtain a vertical synchronizing pulse corresponding to substantially the occurrence of pulses V, graph b, the output energy of the circuit 19 is applied to the threshold clipper 32 which is adjusted for a clipping operation at level 45 which clears the positive undulation 37 but clips the maximum undulation 38 produced from pulses V. By shaping the clipped portions at 46 pulses 47 are obtained, as indicated in graph e, for application over connection 48 to the reproducer 17. While the timing of the pulses 47 is slightly delayed with respect to the pulses V, it will be noted that each pulse 47 occurs shortly after the occurrence of the leading edge of each vertical blanking pulse VB of graph a so, that the vertical retrace period is initiated during the blanked out portion which of course is provided of ade-

quate duration to permit completion of the vertical scanning period between picture frames.

While I have not shown a provision for interlacing it will be clear to those skilled in the art that my system by reason of its susceptibility to pulse timing, is adaptable to interlaced scanning. For an understanding of the selective reception of multiple picture television transmission a discussion of the problems of interlacing of the successive frames is not now necessary.

In order to select the corresponding sound channel from the multi-channel train detected at 18 and indicated in graph b of Fig. 2, the train of pulses is applied over connections 18a and 18b to a channel selecting mixer 49. The mixer 49 is normally blocked thereby requiring deblocking pulses for passage of signal pulses. The deblocking pulses are produced from the train of pulses 43 employed as horizontal synchronizing pulses. The pulses 43 are applied over connection 50 to a shaper 51 whereby pulses of a desired width as indicated at 52, graph f, are produced one for each of the pulses 43. The output of shaper 51 is applied to an adjustable delay device 53 which may be of the passive inductance-capacitance network type in itself well known as a retardation line having adjustable contacts or it may include an electronic type of timing circuit that is adjustable for retarding pulses. Examples of such delay devices as applied to pulse work may be seen in application Ser. No. 435,498 by D. D. Grieg for "Delay circuits," filed Mar. 20, 1942, issued U. S. Patent No. 2,419,546, Apr. 29, 1947, and Ser. No. 461,307 by H. G. Busignies for "Calibration arrangement," filed Oct. 8, 1942, issued U. S. Patent No. 2,471,408, May 31, 1949. For passage of the pulses of channel 1, the deblocking pulses 52 are retarded an amount t_1 as indicated at 52a. The retarded pulses 52a are applied to the mixer 49 which is provided with a threshold clipping bias as indicated at 54 in graph g. The pulses 1 are superimposed upon the deblocking pulse energy 52a and thereby clipped for application to limit amplifier 55. Limit amplifier 55 amplifies the pulse energy output of mixer 49 to a given amplitude which is thereafter applied to a time modulation demodulator 56 for translation of the time displacement of the signal pulses to amplitude displacements from which audio energy is obtained through low-pass filter 57. The audio energy is applied to a sound reproducer 58 such as the usual speaker in a television receiver.

No particular type of time modulation of the signal pulses is required according to the principles of my present invention. By way of illustration I have shown one form of time modulation where the signal pulses 1, 2 and 3 are time displaced relative to a normal timing of such pulses in the absence of modulation. The time displacements from the normal time positions or in other words relative to the timing of the leading edges of the pulses H and V, graph b, represent increments of the modulating energy and may be translated into pulses of varied amplitude in accordance with the time displacement of the corresponding signal pulses. Another type of time modulation that may be employed for the signal modulation is the so-called "push-pull" time modulation where the successive pulses are time displaced toward and away from each other in accordance with the instantaneous values of the modulating energy. In either case the T. M. demodulator such as illustrated in Fig. 4 may be employed.

In the illustration of Fig. 1 the limit amplifier

55 is shown to have an input connection controlled by switch 59 through which pulses 43 may be applied from shaper 42. Pulses 43 are in such instance used as bench mark pulses from which the time displacement of the signal pulses may be measured. These bench mark pulses 43a, graph h, are shown in their time relation relative to the pulses of channel 1 as received from the limit amplifier 55 for application to the demodulator 56. The pulses are applied over connection 60 to the demodulator 56, Fig. 4, and are applied to the main grid 61 of vacuum tube 62. Connected to the screen grid 63 is a shock excitable resonant circuit 64 to which is applied a source of positive potential at 65. The suppressor grid 66 is connected through a resistor 67 of high value to ground. The plate 68 is connected to a low resistor 69 which is shunted by a condenser 70 to output 71 which is connected to filter 57, Fig. 1.

20 In operation of the demodulator circuit of Fig. 4, the resonant circuit 64 is tuned to a frequency, the period of which is preferably a harmonic of the cadence frequency of the pulses applied to the demodulator over input connection 60, although 25 it may be tuned to the same frequency as that of the pulse cadence. When a pulse is applied to the grid 61 the amplitude thereof is such as to effect a passage of energy to the screen grid 63 thereby establishing an oscillatory wave 72 such as indicated in graph i. The voltage of this oscillatory wave is applied to the screen grid 63. It will be understood that this wave is of damped characteristics, the damping thereof depending largely upon the Q of the circuit 64. Circuit 64 is so 30 tuned as to provide a wave which normally passes through the pulse position points of graph h when the pulses are in the position normally assumed in the absence of modulation. Where the pulses are grouped in pairs with relatively close spacing 35 between the pairs, the wave 72 may pass through but one cycle between the pulses of a pair although this depends upon the tuning of circuit 64. By tuning circuit 64 the wave may be caused to pass through a half-cycle or several cycles between adjacent pulses.

40 The tuning, however, must bear a definite relation to the pulse timing similarly as illustrated in the drawing so that the signal pulse 1a will occur during a lineal portion of the wave. Since 45 the pulse 1a is at one limit of modulation such as the negative maximum of the signal wave, it may be caused to occur at the point where the wave crosses the zero axis as indicated at 73, although it may be caused to occur at some other point such as below the zero axis if desired.

50 The pulse 1a shock excites the circuit to renew with added vigor the oscillations as indicated at 74. The bench mark pulses 43a also shock excite the circuit 64 in like manner to pulse 1a. Pulse 55 1b occurs on a lineal portion of the wave at a point 75 above the zero axis thereby causing the oscillatory swing to exceed those produced by pulses 43a and 1a. The oscillations following the pulse 1b, while of a larger swing than the wave preceding pulse 1b, nevertheless provide the desired linear increasing potential at the occurrence of the next pulse 43a and the oscillation following such pulse produces a linear increasing portion for any position that pulse 1c may assume. It 60 should also be noted that the stable regular occurrence of the bench mark pulses 43a has a 65 steadyng effect on the demodulating wave which improves the lineal translation of the time displacements of the channel pulses.

70 75 The threshold clipping level of the tube 62 is

so chosen as to occur at the peak of the wave potential produced by the bench mark pulses or those channel pulses in the position indicated for pulse 1a. This clipping level is indicated at 16 and produces an output of pulses as indicated by graph j, the amplitude variations of which define the envelope 17 of the original modulated signal wave.

For a further discussion of the demodulating features of the type of demodulator circuit shown in Fig. 4 reference may be had to the Patent to D. Grieg No. 2,416,306, issued February 25, 1947.

From the foregoing description it will be clear that in accordance with my invention the receiver of Fig. 1 is capable of selecting by tuning of the amplifier 14 any of the picture programs broadcast from the tower 5. By ganging the tuning control indicated at 18 for amplifier 14 with the adjustment control 19 of the delay device 53 the sound channel corresponding to the selected picture carrier will be automatically segregated from the multi-channel transmission received by amplifier 15. In this connection it will be clear to those skilled in the art that the multi-channel transmission may include broadcasts other than sound signals for the picture programs. In other words, sound signals may be included for other sound programs for radio transmission and in addition other channels may be provided for facsimile transmission. The gang connection 30 between the control 18 and 19 may therefore be interrupted to provide independent adjustment of the delay device for reception of broadcasts other than television.

While I have shown and described my invention in connection with specific apparatus it will be understood that the illustration is given by way of example only and not as limiting the scope of the invention as set forth in the objects and the appended claims.

I claim:

1. In a television system wherein a plurality of picture programs are transmitted on separate carriers and the sound signals corresponding to each program are transmitted as one of the channels in a multi-channel carrier separate from the picture carriers; a method of selectively receiving one of the transmitted picture and sound programs comprising detecting the picture carrier having the desired picture program, detecting the multi-channel carrier, deriving from the multi-channel carrier energy common to the picture and sound programs, applying the derived energy to the multi-channel carrier, and under control of said derived energy, segregating from the channel signals the sound signals corresponding to the selected picture program and reproducing from said detected picture signals, said derived energy and the segregated sound signals, the desired picture and sound program.

2. In a television system wherein a plurality of picture programs are transmitted on separate carriers and the sound signals corresponding to each program are transmitted as one of the channels of a multi-channel carrier different from the picture carriers, one of the channels of said multi-channel carrier comprising synchronizing pulses common to all of the picture programs, a method of selectively receiving one of the picture and sound programs comprising detecting the carrier modulated with picture signals of the desired picture program, detecting the multichannel carrier, selecting from the multichannels the channel having the synchronizing pulses, segregating, under control of the syn-

chronizing pulses, from the multichannels, the channel having the sound signals corresponding to the selected picture program, reproducing under control of said synchronizing pulses the picture program transmitted by said picture signals, and reproducing the sound transmitted by the segregated sound signals.

3. A television receiver for receiving a picture program wherein the picture signals thereof are transmitted over one carrier and the accompanying sound signals and synchronizing signals are transmitted by different channels over a second multiplexed carrier, comprising means for detecting said one carrier to obtain the picture signals, means for detecting said second carrier to obtain the sound and synchronizing signal energy, means for separating out the synchronizing signals, means for deriving the multi-channel carrier energy common to the picture and sound programs, and under control of said derived energy for segregating from the channel signals the sound signals corresponding to the selected picture program, a picture reproducing device, means to apply said synchronizing signals to said device to control the reproduction of said picture program, and means for reproducing the sound of the picture from said sound signals.

4. A television receiver for receiving a desired one of a plurality of picture programs wherein the picture signals of the different programs are transmitted on separate carriers and the sound signals accompanying each program are transmitted as one of the channels in a multi-channel carrier, comprising means for detecting the carrier of the desired picture program to obtain the picture signals thereof, means for detecting the multi-channel carrier, means for deriving from the multi-channel carrier energy common to the picture and sound programs, and means under control of said derived energy means for segregating from the multi-channel carrier the sound channel corresponding to the selected picture program and for reproducing the picture from the picture signals, and means for reproducing the sound for the picture program from said sound signals.

5. A television receiver comprising means for receiving picture signals transmitted on a given carrier, means for receiving a multi-channel carrier, one channel of which includes the sound signals of said picture signals and another channel of which includes synchronizing signals for said picture signals, means to segregate the synchronizing signals from the received channels, means for reproducing the picture conveyed by said picture signals under control of said synchronizing signals, means controlled by said synchronizing signals for segregating from the received channels the sound channel corresponding to the received picture signals, means for reproducing the sound from the signals of the segregated sound channel, and means coordinating said sound channel segregating means with the picture signal receiving means.

6. A television system comprising means for transmitting a plurality of picture programs on separate carriers, means for transmitting as separate channels on a multi-channel carrier the sound signals corresponding to the separate picture programs, said last named means including means for transmitting synchronizing signals common to all of said picture programs as one of the channels of said multi-channel carrier, and means for radiating the picture carriers and said multi-channel carrier; a receiver for

simultaneously receiving a desired one of said picture carriers and said multi-channel carrier, means for segregating from said multi-channel carrier the pulses of the synchronizing channel, means for reproducing the picture from the received picture signals under control of said synchronizing signals, means for receiving and reproducing from the multi-channel carrier under control of said synchronizing signals the sound signals corresponding to the selected picture program.

7. In a television receiver having means for receiving a desired one of a plurality of picture programs transmitted on separate carriers and means for receiving a train of synchronizing pulses common to all of said picture programs transmitted on a carrier separate from said picture carriers, the synchronizing pulses being timed according to line scanning of the picture signals with certain of the pulses differing in width from others to represent the timing of successive frame scanning intervals; means for obtaining line and frame synchronizing pulses from said train comprising a pulse width discriminator to produce an undulation of a given polarity in response to the leading edge of each pulse and to produce an undulation of opposite polarity in response to the combined action of the leading and trailing edges of each pulse, said discriminator being arranged to vary the amplitude of said undulations of opposite polarity according to the width of the pulses, whereby the undulations responsive to said certain pulses are of greater amplitude, means to pass energy of said undulations of given polarity for use as line scanning synchronizing pulses and means to clip the undulations of said greater amplitude for use as frame scanning synchronizing pulses.

8. In a television receiving system having means for receiving a multi-channel train of pulses, one channel of which comprises pulses of width greater than the pulses of other channels, the pulses of said one channel being timed according to line scanning, with certain of the pulses thereof differing in width from others to represent the timing of successive frame scanning intervals; means for obtaining line and frame synchronizing pulses from the train of pulses comprising a pulse width discriminator to produce an undulation of a given polarity initi-

10

ated by the leading edge of each pulse of said train and to produce a maximum undulation of opposite polarity in response to the combined action of the leading and trailing edges of each pulse, said discriminator being arranged to cause the amplitude of the undulations produced from the pulses of said other channels to be small in comparison with the undulations produced from the pulses of said one channel, and those maximum undulations of said opposite polarity resulting from the pulses of said one channel are of greatest amplitude for said certain pulses, means to clip the undulations of said given polarity at a level beyond the amplitude of the undulations resulting from the pulses of said other channels to obtain pulses for use as line scanning synchronizing pulses, and means to clip those undulations of said opposite polarity that are of greatest amplitude for use as frame scanning synchronizing pulses.
